UNITED STATES PATENT OFFICE.

JOHN M. JENKINS, OF CINCINNATI, OHIO, ASSIGNOR TO THE GLOBE FILES COMPANY, OF SAME PLACE.

PAPER-FILE.

SPECIFICATION forming part of Letters Patent No. 325,676, dated September 8, 1885.

Application filed April 4, 1885. (No model.)

To all whom it may concern:

Be it known that I, JOHN M. JENKINS, of Cincinnati, Hamilton county, Ohio, have invented a new and useful Improvement in Paper-Files, of which the following is a specification.

My invention relates to improvements in those receptacles for business documents and other papers in which two rectangular boards are connected at bottom and two sides by an "accordion" gusset, the space thus inclosed being separated into a number of compartments by means of partitions. In my improvement such gusset is composed of as many paper strips as there are compartments, and of which each strip is conterminous with the bottom and two sides of the respective compartment, and is so creased, cut, and overlapped and pasted at the cut parts as to possess an inwardly-extending crimp that serves to distend and permit expansion of the compartment and a pair of flies or wings, each of which and the corresponding wing of the adjacent crimp serve for attachment (by pasting) of the partition.

The formation of the respective parts of the gusset which are included between every two consecutive partitions of an entire strip of paper having wings by which it is pasted to the adjacent partitions, is thought to possess important advantages, both over those files whose gusset portion between each pair of such partitions consists of three strips, and over those whose entire gusset is composed of a single large sheet of crimped paper. Over those of the former class it presents the advantages of accuracy in form and dimensions over such loose and separable strips, of avoiding corner orifices where dust can enter and contents escape, and of its much greater strength and durability at its completely-closed corners on which the principal wear comes. It is also more quickly and therefore more cheaply constructed. Over those files whose gusset is composed of a single sheet it possesses the advantage of attachment of each partition by pasting all around its margin to the crimp-wings, thus holding all the parts in their proper form and making impossible any bulging or demoralization of the crimps or displacement of partitions consequent on the over-

crowding of individual compartments. Hence the shape and efficiency of my file are much longer preserved.

In the accompanying drawings, Figure 1 is 55 a perspective view of a paper-file constructed on my plan. Fig. 2 is a flat view of one of the paper blanks out of which each crimp is formed. Fig. 3 represents a crimp formed out of such a blank by folding and pasting together the corners, accompanied by one of the partitions shown detached. Fig. 4 is a cross-section through three adjacent crimps and two attached partitions.

A A' represent two similar cheeks or sides, 65 preferably of card-board or pasteboard and of rectangular shape. An extension of one of these sides may form a flap, a.

B represents leaves or partitions of corresponding shape and dimensions to the sides, 70 and of any suitable material, such as stout Manila paper.

C represents a blank of tough Manila paper or other suitable material, which, when partially severed, crimped, bent, lapped, and 75 pasted so as to assume the form shown in Fig. 3, becomes one of the component members or gores of my gusset, there being one such member for each space or pocket formed by the neighboring partitions and by the end partitions and the neighboring cheeks. Each of such blanks, having been partially divided by transverse cuts c, corresponding to the locations of the file-corners, as shown in Fig. 2, is 80 triply crimped, as shown at c' c'' c''' in Fig. 3, 85 and its cut portions bent, lapped, and pasted, as shown at c^{iv} c^v of that figure.

The portions of the strip C outside of the external crimps, c' and c'', form two flies or wings, D D', to whose outer faces, d, and to 90 corresponding faces of the neighboring and identically-similar gores the lower and end marginal portions of two consecutive partitions are pasted. The two end partitions are in like manner connected to the cheeks A A'. 95

The gusset may at or near its free or exposed edges be strengthened by a re-enforce or binding, E, which, being pasted to said gusset and to the outside of the cheeks, prevents the separation of these parts by use.

Of a number of obvious advantages of this construction over that in which the gusset is

made to consist of a single sheet is the capacity of building up a file of any desired number of compartments, greater or less, to order, without change or waste of material.

5 The binding or re-enforce E, being continued around the outside of the outer pieces or cheeks, becomes a binding to the latter as well as to the gusset. I do not claim, broadly, the strengthening of gusset-margins by re-en-

10 forces pasted thereto, such being old.

I claim as new and of my invention—

1. A paper-file consisting of the combination of cheeks A A', partitions B, and partially severed, crimped, bent, lapped, and pasted 15 gores or gusset sections formed from blanks C, Fig. 2, which, having been partially severed by cuts c that extend transversely from each edge inward at the places for the file-corners, are interiorly crimped, as shown at 20 c' c'' c''', Fig. 3, each section having wings D D', to which the lower and end marginal portions of the said cheeks and partitions are pasted, as and for the purposes set forth.

2. In a paper-file, the combination of the 25 cheeks A A', the partitions B, the crimped

and folded gusset-sections C, each of which is conterminous with the bottom and sides of the partitions B, each of said partitions being secured between the wings D D' of two consecutive gusset-sections, and the re-enforce E, 30 pasted to the outer side of the upper margins of the gussets to prevent their separation, substantially as set forth.

3. In a paper-file, the gusset composed of gores or sections formed from blanks C, Fig. 35 2, which, having been partially severed by cuts c that extend transversely from each edge inward at the places for the file-corners, are interiorly crimped, as shown at c' c'' c''', Fig. 3, one section being applied to each compartment, each section being partially severed, crimped, bent, lapped, and pasted, and having wings D D' for attachment by pasting of the 40 partitions B, in the manner set forth.

In testimony of which invention I hereunto 45 set my hand.

JOHN M. JENKINS.
